UNITED STATES PATENT OFFICE.

SAMUEL COHN, OF NEW YORK, N. Y., ASSIGNOR TO MANTLE MACHINERY & PATENTS COMPANY, OF NEW YORK, N. Y., A CORPORATION OF NEW YORK.

MACHINE FOR SEWING MANTLES.

1,145,556.

Specification of Letters Patent.

Patented July 6, 1915.

Original application filed March 22, 1912, Serial No. 685,557. Divided and this application filed February 25, 1913. Serial No. 750,607.

To all whom it may concern:

Be it known that I, SAMUEL COHN, a citizen of the United States, and resident of New York city, in the county and State of New York, have invented a new and useful Improvement in Machines for Sewing Mantles, of which the following is a full, clear, and exact description, reference being had to the accompanying drawings, forming 10 part of this specification, in which—

Figure 1 is a side elevation of a combined mantle shirring and sewing machine embodying my invention; Fig. 2 is a partial plan view; Fig. 3 is a partial side elevation showing another position of the parts; Figs. 15 4 and 5 are cross-sectional views on the lines IV—IV and V—V respectively of Figs. 1 and 3; Figs. 6, 7 and 8 are detail views of modified forms of threadder hooks; Fig. 9 is a sectional elevation of the center 20 member; Fig. 10 is a sectional side elevation showing another form of machine; Fig. 11 is a top plan view of Fig. 10; Fig. 12 is a partial side elevation showing the parts 25 of the second form of machine in another position; and Fig. 13 is a cross-section on the line XIII—XIII of Fig. 10.

The present application is a division of my copending application Serial No. 685,557, 30 filed March 22nd, 1912.

The present invention has relation to mechanism for passing the gathering or shirring string through the mantles; and is 35 designed to provide a cheap and effective machine of this character which is not likely to get out of order.

The invention consists broadly in providing a machine having fixed needles over which the mantle is pushed after or during 40 plaiting, together with shirring mechanism arranged to shir the mantle and force the shirred or plaited fabric over the needle. It also comprises threading mechanism for the needle, together with other features of construction, arrangement and combination of the parts as hereinafter described and pointed out in the appended claims.

Referring to the form of machine shown 45 in Figs. 1 to 9, inclusive, in which fixed needles are employed, the numeral 2 designates a lever, mounted on a shaft having a bevel wheel 3, meshing with a mutilated wheel 4 on the oscillating hand shaft 5.

The rock lever 2 has a pivotal link 6 con-

nected to a horizontally moving slide, this 55 slide being in the form of a double rack having teeth 8, 8 on opposite sides. The teeth of these racks engage the corresponding teeth of spur wheels 9, 9, each carried on a shaft 10 having a toothed wheel 11. The 60 wheels 11 act as the side or shirring members of the device, the center shirring member 12 of which is fixed to and projects up vertically from the slide 7. This member is preferably of the cross-sectional form shown 65 in Fig. 9, having needle-receiving recesses 13 at each side thereof and in line with the corresponding recesses of the wheels 11 so that the parts may pass over said needles.

The two needles 14 are rigidly secured in 70 parallelism to a block 15 having holes receiving stems 16 on which the block may slide, it being normally held forward by spiral springs 17. The stems 16 are adjustably secured in a standard 18, which is 75 shown as projecting up from one of the bearings for the hand shaft 5, having the handle 19.

In order to thread the needles at the proper time, I preferably employ an oscillating arm or rocking lever 20, as shown in 80 Fig. 4, which is operated by the pin 21 on the main shaft 5 projecting through a slot 22 in the loose collar which carries this arm. At the end of this lever 20 is carried the 85 threadder hook 23, which may be of any desirable form, such as shown in Fig. 2 or in Figs. 6, 7 and 8, for example.

The arm 20 when released is returned to 90 a position against the stop 24, as shown in Fig. 4, by means of a spiral spring 25 secured at one end to a pin 26 on the arm 20, and at its other end to the frame at the point 26°.

The operation of the device is as follows:—When the handle 19 is moved back, the center member 12 of the folders is moved toward the needles and at the same time the side folder members 11 are revolved. The mantle having first been placed on the center member, the teeth of the side members will engage the recesses of the center member and crimp the mantle. As these crimps or plaits are formed they are progressively pushed forward upon the needles plait by 105 plait, by the movement of the center member. By the time that the center member contacts with the block 15, all of the plaits

of the mantle will have been fed upon and over the needles. The further continued movement of the center member will then push the needle block 15 back toward the upright 18, compressing the springs and moving the needles back free from the side members; that is, from the position shown in Fig. 1 to the position shown in Fig. 3. This exposes the eyes of the needles, and 10 simultaneously with the moving back of the needles the lever 20 moves transversely toward the needles by the operation of the pin on the shaft, the timing being such that the eyes are in position to receive the threader hook when it reaches them.

When the threader hook has passed through the eyes, it is threaded and the needle is then moved back. At the same time, the operation of the spring 25 carries 20 the threader lever away from the needles, thus performing the threading operation. As the threader hook issues from the needle eyes, either the operator's hand or a suitable mechanical device engages the end of 25 the thread carried by the threader hook and holds it within the threader hook until the latter receives its full movement from the needle eyes. The object of this is to so place the thread length that the center point thereof shall be at a point midway between the needles. The continued return movement of the handle will cause the center member to move back with the plaited or crimped fabric thereon. The operation of 30 the springs 17 will cause the needles to move back to their normal position, and the further return movement of the center member will carry the plaits over the thread and thus thread the cord through the plaits as 35 the parts move back to their normal position. The mantle may then be lifted off and another blank placed on the center member and the operations repeated. The advantages of this form of the apparatus result 40 largely from the use of the stationary needles, thus simplifying the apparatus and making it easier to construct and keep in order. Moreover, the plaits are carried over the needle one by one as they are formed.

50 In Figs. 10 to 13, inclusive, I show another form of machine which is illustrated as provided with fixed needle mechanism like that of the form first described. In the second form, parts similar to those of 55 the first form are designated by similar numerals with the letter "a" applied. The lever 2^a is provided with the link 6^a connected to the central slide. The slide in this case consists of a bar 27 having a longitudinal slot 28. The bottom of this slot is closed by a bar or plate 29 secured to bar 27 by screws 30 and having transverse vertical slots. Through these slots in the floor of the central member extend pairs of vertical pins to uprights 31 having vertically ex-

tending slots 32 shown in Fig. 13. Through these slots 32 extend rods 33 running longitudinally of the slide and acting as guides. These vertically movable uprights, or pin standards, ride at their lower ends on the 70 longitudinal cam members 34, which are secured to the frame of the machine underneath the slide.

Each upright is provided at its lower end with a side extension 35, which extension 75 operates with a cam 36 shown in Figs. 10, 12 and 13. These stationary cams 36 cause the standards to move down over the beveled end portion of the cams 34.

An upright plate 37 has a flange or base 80 portion screwed to the bar 27 near one end thereof, and an upwardly projecting pin 38 is set in the other end portion of the bar. The needle block 15^a carries a forwardly projecting rod 39 surrounded by a spring 40, 85 which extends between the block and a pin 41, the other end of the rod having a pin 42 acting against the block. A front plate 43 is grooved to allow the passage of the pin 38 and is fixed to the front end of rod 90 39. Secured to the upright 18^a is a pivoted hook 44 normally held down by spring 45, this being arranged to interlatch with the pin 42 on the rod 39. The needle block is 95 slidingly carried on rods 46 having surrounding spiral springs 47, and the depending pin 48 on the needle block interlaces with horizontally swinging hook 49 pivoted to the upright 18^a. The arm 20^a in this form of machine corresponds to the arm 20 in the 100 form first described, it being operated in one direction by the pin 21^a on the main shaft 5^a, and which pin projects through the slot 22^a in the loose collar which carries the arm, and being returned by the spring 25^a connected thereto. In the operation of this 105 form of machine, a tubular mantle is slipped on the uprights 31, which act as the central folding member. The movement of the handle will then cause the slide to move toward 110 the needle block. As this movement continues, the uprights or pins 31 riding on the cam 34 will be progressively moved down and out of the fabric by the cam 36 operating on the extensions. As these uprights 115 are successively moved down the fabric is formed into plaits by the co-operation of the uprights and the revolving side members 11^a which are actuated by pinions and side teeth or racks 8^a as in the first form; and these 120 plaits will be laid plait by plait against the front plate 43, each upright emerging from the fabric as the next upright approaches the contact point and is ready to hold the plaited fabric pressed between itself and the 125 grooved plate. By the time the last upright is ready to move entirely out of the fabric, the plate 37 will be in a position to hold the plaited fabric pressed between itself and the plate 43, as shown in Fig. 12. The con- 130

tinued movement of the slide will then push the rod 39 back toward the needle block, compressing the surrounding spring until the pin 42 interlaces with hook 44. This moves the fabric farther back on the needle, and it will be noted that at the time the needles enter each plait the uprights have already moved down and out. In other words, each plait as it is formed is fed onto the needles immediately after the uprights have emerged therefrom. The further movement of the slide will cause the pin 38 on the bar or slide to bear against the needle block 15^a to carry it back on its rods until the depending pin 48 interlaces with hook 49. This moves the needles back from the side members so as to expose the eyes for threading. The threading arm 20^a and threading hook 23^a and allied parts act the same as in the first form. On the return movement of the handle, the pin marked 50 on the handle 19^a engages hook 44, releasing the same from the pin 41 and allowing the spring 40 to come into action, thus pushing the plate 43 away from the needle block. This operation results in carrying the thread back through the fabric and pushing the mantle partly or wholly off the needles. During this action, the hook 49 is latched on the pin 48, thus holding the needle block in retracted position. The continued movement of the handle will then release hook 49 by the direct engagement of some part of the handle with the lever arm part 51 of this hook. This will allow the block and needles to return to their normal positions. The mantle may then be removed, and another mantle blank applied and the operation repeated.

The advantages of my invention result from the simplicity of construction and arrangement of the parts, and from the ease and rapidity with which the operations may be performed. The machines are not liable to get out of order, the parts are comparatively few in number, and the operations are positive and effective.

It will be obvious that various changes can be made in the construction, arrangement and combination of the parts, and in the details thereof, without departing from the spirit and scope of my invention as defined in the appended claims.

I claim:—

1. In a mantle shirring machine, a pair of relatively stationary needles having eyes in their pointed ends, and shirring mechanism arranged to first shir the mantle and force the shirs or plaits after their formation over the needles, while said needles are substantially stationary, said shirring mechanism being movable to a position to expose the needle eyes when the material has been placed on said needles.

2. In a mantle shirring machine, a pair of relatively stationary needles, shirring

mechanism arranged to shir the mantle and force the shirred or plaited fabric over the needles while said needles are substantially stationary, and threading mechanism for said needles; substantially as described. 70

3. In a mantle shirring and sewing machine, a pair of relatively stationary needles, shirring mechanism arranged to move the plaited fabric over the needles while said needles are substantially stationary, means 75 for moving the needles free of the shirring mechanism, and threading mechanism arranged to operate on the free eyes of the needles; substantially as described.

4. In a mantle shirring and sewing machine, a movable needle block having relatively stationary needles, shirring mechanism arranged to plait the fabric and force the same over the needles while the latter are substantially stationary, means for moving the needles backwardly to free the eyes, 85 and threading mechanism; substantially as described.

5. In mantle shirring machines, a pair of side folders, a central folder arranged to 90 successively form plaits and withdraw therefrom, mechanism for holding the compacted mass of plaits, needles, mechanism for causing said needles to extend therethrough, and threading mechanism for the 95 needles; substantially as described.

6. In mantle shirring machines, a pair of side folders, a central folder made in a plurality of parts, connections arranged to remove said parts as the plaits are successively 100 formed, mechanism for holding the plaits compacted together, and needle mechanism coacting with the plaits to pass the thread therethrough; substantially as described.

7. In mantle shirring machines, a pair of side folders, a central folder made in a plurality of parts, connections arranged to remove said parts as the plaits are successively 105 formed, mechanism for holding the plaits compacted together, and a pair of relatively 110 stationary needles, over which the plaited mass is arranged to pass; substantially as described.

8. In mantle shirring machines, a pair of side folders, a central folder made in a plurality of parts, connections arranged to remove said parts as the plaits are successively 115 formed, mechanism for holding the plaits compacted together, and a pair of relatively 120 stationary needles, over which the plaited mass is arranged to pass, and threading mechanism for the needles; substantially as described.

9. In mantle shirring machines, a pair of side folders, a central folder made in a plurality of parts, connections arranged to remove said parts as the plaits are successively 125 formed, mechanism for holding the plaits compacted together, a movable needle block, a pair of relatively stationary needles 130

mounted in the movable needle block, over which the compacted mass is arranged to pass, and mechanism for moving the block back to clear the needle eyes, and threading mechanism therefor; substantially as described.

10. In a mantle stirring machine, a folding mechanism comprising coöperating relatively movable members having inter-
10 fitting portions to plait or shir the tubular fabric, a needle, connections for causing the needle to extend transversely through the body of plaits, and connections for withdrawing at least parts of both coöperating
15 members of the folding mechanism from the fabric plaits before the thread is passed into the fabric by the needle.

11. In a mantle stirring machine, the combination with a needle, of plaiting
20 means including a fabric carrying member having a back and forth movement longitudinally of the needle and toward and from the same to place the plaited fabric on said needle, and means for threading the needle
25 when the fabric is thereon.

12. In a mantle stirring machine, the combination with spaced needles, of spaced rotary folding members, a central reciprocating member operating between
30 the rotary members, and means for reciprocating the central member to cause it to move by the rotary folding members and place spaced portions of the folded material on the needles.

35 13. In a mantle stirring machine, the combination with a relatively fixed needle supported at its rear end and having an eye at its point, of means for folding fabric and placing it on said needle over the point,
40 said folding means and needle being relatively movable to a relation to leave the eye exposed to be threaded while the fabric is thereon.

14. In a mantle stirring machine, the
45 combination with a relatively fixed needle supported at its rear end and having an eye

at its point, of means movable toward and from the point for folding fabric and placing it on said needle over the point leaving the eye exposed, and means operating transversely of the needle for threading the exposed eye.

15. In a mantle stirring machine, the combination with a needle having an eye at its point, of fabric folding means, said means being movable toward and from the needle for placing the folded fabric thereon, and means for holding the folded fabric in compacted form on the needle with the eye of said needle exposed.

16. In a mantle stirring machine, the combination with a needle having an eye at its point, of fabric folding means, said means being movable toward and from the needle for placing the folded fabric thereon, a yielding abutment for the folded fabric associated with the needle, and a device movable with the folding means for pressing the fabric in compacted relation against said abutment and moving the latter to expose the needle eye.

17. In a mantle stirring machine, the combination with spaced needles, of means supporting the same at their rear ends, said needles having eyes at their points, of a rotary fabric folding member located in advance of the point of each needle, a reciprocating member that operates between and co-acts with the rotary members, said reciprocating member moving past the points of the needles to place the fabric thereon, means for moving the fabric to a position on the needles to expose the eyes of said needles, and means for threading the needles when the eyes are so exposed.

In testimony whereof, I have hereunto set my hand.

SAMUEL COHN.
